(57) **CLAIM**

The ornamental design for a top cover for a mower as shown and described.

DESCRIPTION

FIG. 1 is a top perspective view of the top cover for a mower showing my new design;

FIG. 2 is a rear perspective view thereof;

FIG. 3 is a top view thereof;

FIG. 4 is a rear view thereof;

FIG. 5 is a front view thereof;

FIG. 6 is side view thereof; and,

FIG. 7 is another side view thereof.

The broken lines in the drawings illustrate portions the top cover for a mower which form no part of the claimed design.
